(57) **CLAIM**

The ornamental design for a furniture component, as shown and described.

DESCRIPTION

FIG. 1 is a front elevational view of a furniture component showing my new design.

FIG. 2 is an enlarged front elevational view thereof.

FIG. 3 is a front elevational view thereof, depicting the knob shaded for the color gray, mounted on a wood panel shaded for the color brown

FIG. 4 is a top plan view thereof, with the right-side and left-side elevational views thereof, and the bottom plan view thereof, being identical; and,

FIG. 5 is a perspective view of the top and front thereof, with perspective views taken at the same angle, but in different directions, being identical.

The rear thereof forms no part of the claimed design.

The broken lines in FIG. 1 depict environment and form no part of the claimed design.

1 Claim, 3 Drawing Sheets

FIG. 1

FIG. 2

FIG. 3

FIG. 4

FIG. 5
